UNITED STATES PATENT OFFICE

ROBERT H. PITTMAN, OF PITTSBURGH, PENNSYLVANIA

DESIGN FOR A COMBINATION DISH

Application filed February 9, 1933. Serial No. 47,154. Term of patent 14 years.

To all whom it may concern:

Be it known that I, ROBERT H. PITTMAN, a citizen of the United States, residing at Pittsburgh, in the county of Allegheny and State of Pennsylvania, have invented a new, original, and ornamental Design for Combination Dish, of which the following is a specification, reference being had to the accompanying drawing, forming part thereof.

Fig. 1 is a top plan view of my combination dish; Fig. 2 is a side elevation of the same; and Fig. 3 is an inverted plan view of the same.

I claim:

The ornamental design for a combination dish, as shown.

ROBERT H. PITTMAN.
